UNITED STATES PATENT OFFICE.

THOMAS A. HIBBINS, OF WELLSVILLE, OHIO, ASSIGNOR TO THE STEVENSON COMPANY, OF WELLSVILLE, OHIO.

ROTARY KNIFE FOR HYDRAULIC OR STEAM SEWER-PIPE PRESSES.

Application filed July 24, 1926. Serial No. 124,742.

My invention relates to improvements in rotary knives for hydraulic or steam sewer pipe presses.

The object of my invention is to provide a 5 rotary knife for a hydraulic or steam sewer pipe press arranged within the lower end of the die and adapted to be normally retracted so as to be in beyond a path with the inner face of the pipe, so as to allow a free passage 10 of the pipe in its formation from the die, and pertains particularly to a structure to be applied to my improved hydraulic sewer pipe press, and my improved die, as shown in the application Serial No. 124,741 filed 15 July 24, 1926.

Another object of my invention is to provide a rotary knife of this character which is automatically moved outwardly by centrifugal force by the rapid rotation thereof, 20 to cause it to sever the pipe close to its discharge from the die, and so constructed and arranged that the die head can be forced up into the die to form a socket on the lower end of the pipe.

25 A further object of my invention is to provide a rotary knife of this character which can be readily assembled in the die of the form herein shown and fully set forth in my copending application heretofore referred to, 30 and which can be readily removed for replacing any of the worn or broken parts.

35 A still further object of my invention is to provide a knife of this character which is very effective in its operation and will absolutely retract so that it will not interfere with the forming of the pipe and the socket during the normal operation of the pipe press, and provide a knife having certain 40 details of structure and combination of parts hereinafter more fully set forth.

In the accompanying drawings:—

Figure 1 is a vertical sectional view of the lower end of the clay cylinder showing the die carried thereby, and my improved knife applied thereto in its outward or cutting position.

Figure 2 is an enlarged top plan view partly in section of my improved knife.

Referring now to the drawings, 1 represents the lower end of the clay cylinder through which the clay is forced by means of the plunger head, all of which is fully shown and described in the application heretofore mentioned, and which needs no further description. The lower end of the clay cylin-

der 1 is provided with an outwardly extending flange 2, to which is bolted the arch ring 3 supporting the arch 3' forming a liner therefor and which is provided with the three inwardly extending webs 4, provided with the hollow cylindrical central portion 5, extending downwardly. This central portion 5 is internally threaded and into which is screwed the solid cylindrical member 6, provided at its lower end with the externally threaded reduced portion 7. Screwed upon this reduced portion 7 is the die member 8 which forms the central portion of the die, and is provided with the outwardly diverging wall 9. Bolted to the arch 70 3 is a flange 10, carried by the upper end of the choke ring 11, which is provided with a liner 12, having the inwardly obliquely arranged wall 13 terminating in the vertical wall 14. Extending from the vertical wall 14, this ring is provided with an outwardly obliquely arranged wall 15, terminating in a plane with the lower end of the choke ring 11. The choke ring 11 at its lower end is provided with an annular flange 17 to which is bolted the annular flange 18, carried by the outer die member 19. The annular flange 17 is provided with an annular downwardly extending flange 20, provided with set screws 21, adapted to engage the flange 18 of the die, and adjust the die member 19 laterally 80 85 so as to bring the oblique wall 22 flush with the wall 15 of the liner 12.

The lower end of the die 19 is flared outwardly as indicated at 23, so as to form a 90 space for forming a socket on the lower end of the pipe, all of which is fully set forth in the application heretofore mentioned. Arranged close to the clay cylinder is an electric motor 24 driving a train of gearing 25, which in turn drives the shaft 26. The train of gearing is provided with a magnetic clutch 27 by means of which the shaft 26 is connected and disconnected from the train of gearing for stopping and starting the knife. The shaft 26 extends horizontally through the arch ring 3, and is provided with a bearing 28 arranged therein, and the arch 3' is provided with an opening 29 which extends in through one of the webs 4. The inner end of the shaft extends within the central hollow portion 5, formed at the inner ends of the webs. The bearing 30 is arranged in the web for the inner end of the shaft 26 and carried by the inner end of the 95 100 105 110

shaft 26, within the central portion 5 is a beveled gear 31 meshing with a bevel gear 32, carried by the vertical shaft 33. The shaft 33 extends downwardly through an opening in the member 6 and is provided at its upper end with a bearing 34, and at its lower end with a bearing 35.

Carried by the extreme lower end of the shaft 33 is a collar 36 which carries the knife and by means of which the same is connected to the shaft. Carried by the collar 36, which in reality is a continuation of the shaft 33, is a block 37 held against rotation upon the shaft in any desired manner and having an opening 38 arranged transversely therethrough and in which is secured a cylinder 39. The cylinder 39 is provided, at its outer end, with an outwardly and obliquely arranged integral arm 40 and which carries at its outer end a stub shaft 41 held against rotation. Loosely mounted upon the stub shaft 41 is a sheave 42, which has its outer periphery provided with a groove 43, arranged in alinement with the center of the opening 44, arranged in the end of the cylinder 39. The sheave 42 is provided with the thickened portion 45 to provide for more weight on the sheave so that it will more readily move outwardly by centrifugal force upon the rapid rotation thereof, and also serving as means for attaching the knife 46 thereto. This thickened portion 45 is provided with a recess 47 into which the inner end of the knife 46 extends, and is held therein by rivets or bolts 48. The knife 46 has a curved cutting face 49 which, due to its curve, more gradually cuts as the knife is moved outwardly by centrifugal force.

Carried by the thickened portion 45, adjacent the outer edge thereof, is a bolt 50, for fastening a cable 51 thereto. The cable 51 extends around the sheave in the groove 43, and passes through the opening 44 in the cylinder 39, and through a block or piston 52 arranged within the cylinder, and held therein by means of the member 53. While I have shown this specific means for attaching the cable to the piston or block 52 it will be understood that any desired means can be employed. Arranged within the cylinder 39 is a coil spring 54 having one end bearing against the outer wall 55, and its inner end bearing against the piston or block 52 and normally holding the same in the position shown in Figure 2 of the drawings, so that the sheave is held so as to bring the knife in beyond the inner face of the inner wall of the pipe 56, shown in dotted lines in Figure 2. The end of the cylinder 39 is closed by the screw cap 57 by means of which the piston or block 52 may be inserted or removed from the cylinder.

The forming of the pipe is caused by the

forcing of the clay through the clay cylinder, and discharging it through the restricted passage 19, in the lower end of the die. After the desired length of pipe has been formed by the die the forming mechanism is stopped and the magnetic clutch is set into operation so that the shaft 26 is caused to rapidly rotate by the train of gearing 25, and through the medium of the beveled gears 31 and 34, the shaft 33 is rapidly rotated, causing the block 37 to rapidly rotate and which in turn, by means of centrifugal force, causes the sheave 42 to swing outwardly upon the stub shaft 41 against the tension of the spring 54, causing the knife to gradually cut through the wall of the pipe, starting at the inner face thereof. As soon as the pipe is completely severed from the body of the clay passing from the die, the magnetic clutch is released, and the sheave is moved backward upon the stub shaft 41 by the tension of the spring 54 through the medium of the cable, and the knife 46 moved in a position in beyond the inner wall of the pipe 56.

While I have shown and described this specific means of holding the knife in its inward position it will be understood that the same could be greatly varied without departing from my invention.

Having thus fully described my invention what I claim is:

1. A cutter of the character described comprising a rotary head, an arm carried thereby, a knife pivoted on the outer end of the arm, means for normally holding the knife in an inward position and adapted to be moved outwardly by centrifugal force.

2. A knife of the character described comprising a rotary shaft, an arm carried thereby, a knife pivoted on the outer end of the arm, means for normally holding the knife in an inward position and adapted to be moved outwardly by centrifugal force.

3. A cutter of the character described comprising a shaft, an arm carried by the shaft, a knife pivoted on said shaft, spring means for normally holding the knife in an inward position and adapted to be moved outwardly by centrifugal force.

4. A cutter of the character described comprising a rotary shaft, a knife pivoted on said shaft, and normally held inwardly and adapted to be moved outwardly by centrifugal force.

5. A knife of the character comprising a rotary shaft, a knife pivotally carried thereby and inwardly spring held, and adapted to be moved outwardly by centrifugal force against the tension of the spring.

6. A cutter of the character described comprising a shaft, a knife pivotally carried by the shaft, a sheave carried by the knife, and a spring held cable passing over the sheave for normally holding the knife in its inward

position, and said knife adapted to be moved outwardly by centrifugal force.

7. A cutter of the character described comprising a rotary shaft, a knife pivotally carried by the shaft, a sheave carried by the knife, a cable passing over the sheave, a cylinder carried by the shaft, and having spring means therein for drawing the cable within the cylinder for holding the knife 10 in its inward position, and said knife adapted to be moved outwardly by centrifugal force.

8. A cutter of the character described comprising a rotary shaft, an arm carried there by, a knife pivoted on said arm, spring means carried by the arm for normally holding the knife in an inward position, said knife adapted to be moved outwardly by centrifugal force.

20 9. A cutter of the character described comprising a rotary shaft, a cylinder carried thereby, an arm carried by the outer end of the cylinder, a knife pivoted on the outer end of the arm, spring means within the cylinder for normally holding the knife in an inward position, said knife adapted to be moved outwardly by centrifugal force.

10. A cutter of the character described comprising a rotary shaft, a cylinder carried 30 by the shaft, an obliquely arranged arm carried by the cylinder, a knife pivoted on the outer end of the arm, a sheave carried by the knife, a cable passing over the sheave and into the cylinder and normally drawn inwardly by spring means to hold the knife in an inward position, said knife adapted to be moved outwardly by centrifugal force, against the tension of the spring means.

11. A cutter of the character described 40 comprising a rotary shaft, a cylinder carried by the shaft, an arm carried by the cylinder and arranged at an angle thereto, a knife pivotally mounted on the outer end of the arm, a sheave carried by the knife, a cable fastened over the sheave and extending into the cylinder and connected to a piston therein, a spring within the cylinder normally holding the piston to one end for holding the knife in an inward position, 50 said knife adapted to be moved outwardly by centrifugal force against the tension of the spring.

12. A cutter of the character described comprising a shaft, an arm carried thereby, 55 a sheave pivotally mounted on the arm, a knife removably attached to the sheave, and a spring held cable passing over the sheave, and normally holding the knife in an inward position, said knife adapted to be moved outwardly by centrifugal force.

13. A cutter of the character described comprising a shaft, a weighted member pivotally carried by the shaft, a knife secured to the weighted member, spring means for 65 normally holding the weighted member in-

wardly, and said member adapted to be moved outwardly by centrifugal force.

14. A cutter of the character described comprising a rotary shaft, an arm carried by the shaft, a weighted sheave pivotally mounted on the outer end of the arm, a knife secured to the weighted sheave, a cable passing around the sheave, and a spring arranged to normally draw the cable and holding the sheave inwardly, said sheave adapted to be moved outwardly by centrifugal force.

15. A cutter of the character described comprising a rotary shaft, a head carried thereby, a cylinder carried by the head at one side of the shaft, an obliquely arranged arm carried by the outer end of the cylinder, a sheave pivotally mounted on the outer end of the arm, a knife removably attached to the sheave, a cable passing over the sheave and into the cylinder and secured to the piston therein, a spring surrounding the cable and normally holding the piston to one end of the cylinder, and holding the sheave in its normal inward position, said sheave adapted to be moved outwardly by centrifugal force.

16. The combination with a pipe press, a die having an annular passage, a vertical shaft on the inside of said passage, means for rotating said shaft, and a pivoted knife 95 carried by the shaft and normally held inwardly by spring means and adapted to be moved outwardly by centrifugal force against the tension of the spring means.

17. The combination with a pipe press 100 having a die to form a pipe by an annular passage, a shaft rotatably mounted in the center of said die, means for rotating said shaft, a pivotally weighted knife carried by the lower end of the shaft within the die, spring means for normally holding the knife in its inward position, said knife adapted to be moved outwardly by centrifugal force below the annular passage of the die.

18. The combination with a pipe press, 110 of a die having an annular passage for forming the pipe, a vertical shaft on the inside of the annular passage, means for rapidly rotating said vertical shaft, an arm carried by the lower end of the shaft, a knife pivoted on the outer end of the arm, spring means for holding the knife inwardly beyond the annular passage of the die, said knife adapted to be moved outwardly by centrifugal force across the annular passage 115 of the die.

19. The combination with a pipe press having an arch formed with radial webs, die members carried by the arch, and the radial webs, and forming an annular discharge passage, a shaft passing horizontally through the arch, and through one of the webs, a vertical shaft mounted in the central member of the die and rotated by the horizontal shaft, means for rotating the 120 125 webs.

horizontal shaft, and a knife pivotally mounted on the lower end of the shaft, and normally inwardly spring held and adapted to be moved out across the annular passage of the die by centrifugal force.

20. The combination with a pipe press, of an arch secured to the lower end of the clay cylinder, and having webs extending radially inwardly, die members supported by the arch and the webs, and having an annular discharge passage, a horizontal shaft passing through the arch and through one of the webs, a vertical shaft passing through the central die member and driven by the horizontal shaft, means for driving the horizontal shaft, an arm carried by the lower end of the vertical shaft, a weighted knife carried by the outer end of the arm, spring means for normally holding the knife inwardly beyond the vertical annular passage between the die members, said knife adapted to be moved outwardly by centrifugal force across the annular passage between the die members.
25. 21. A cutter of the character described comprising a shaft, a knife pivoted on said

shaft, means for normally holding the knife in an inward position and adapted to be moved outwardly by centrifugal force.

22. A cutter of the character described comprising a rotary shaft, a head carried by said shaft, a knife pivoted in said head, means for normally holding the knife in an inward position and adapted to be moved outwardly by centrifugal force. 30 35

23. A cutter of the character described comprising a rotary shaft, a knife pivoted in said shaft, spring means for normally holding the knife in an inward position and adapted to be moved outwardly by centrifugal force. 40

24. A cutter of the character described comprising a rotary shaft, a housing carried thereby, an arm carried by the outer end of the housing, a knife pivoted on the outer end of said arm, spring means within the housing for normally holding the knife in an inward position, said knife adapted to be moved outwardly by centrifugal force. 45

In testimony whereof, I have signed this 50 specification.

THOMAS A. HIBBINS.
